CLAIM

The ornamental design for a dual motor standing desk, as shown and described.

DESCRIPTION

FIG. 1 is a top perspective view of a dual motor standing desk showing my new design;

FIG. 2 a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 1;

FIG. 11 is an enlarged view of detail 11 in FIG. 1;

FIG. 12 is an enlarged view of detail 12 in FIG. 2;

FIG. 13 is an enlarged view of detail 13 in FIG. 2;

FIG. 14 is an enlarged view of detail 14 in FIG. 3;

FIG. 15 is an enlarged view of detail 15 in FIG. 6; and,

FIG. 16 is an enlarged view of detail 16 in FIG. 8.

The broken lines in the figures are for the purposes of illustrating portions of the dual motor standing desk, which form no part of the claimed design.
